ROLLER-TRIP FOR PRINTING-PRESSES.

1,249,619.

Specification of Letters Patent. Patented Dec. 11, 1917.

Application filed September 10, 1914. Serial No. 860,982.

To all whom it may concern:

Be it known that we, FRANK O. GUSTAFSON and EDWARD C. GUSTAFSON, citizens of the United States, residing in the city of 5 Portland, county of Multnomah, and State of Oregon, have invented certain new and useful Improvements in Roller-Trips for Printing-Presses, of which the following is a specification.

10 Our invention relates to roller trips for printing presses, and more particularly to movable bearing devices adapted to be operated, after the ink rollers have passed once over the printing form, for the purpose of 15 supporting said ink rollers free from contact with said printing form on their return trip, and thereby prevent any regathering of the ink from said form by said rollers on their return trip.

20 The invention, broadly considered, comprises bearing members movably associated with the form for a printing press, at opposite sides thereof, and adapted when in one position to rest flush with or below the printing surface of the form, and when in their 25 operating positions to project above said printing surface, whereby to carry said ink rollers above and free from engagement with said printing surface. In the preferred embodiment of the invention, we provide a device which is automatically tripped after the 30 ink rollers have passed once over the form. We also prefer to provide a construction in which the ink rollers themselves operate 35 to do the tripping. We also have provided a device which is automatically set with each impression taken by the press.

In order that others may fully understand our invention, we have shown in the accompanying sheet of drawings, one practical embodiment thereof which we will now describe.

Figure 1 is a plan view of a form with our invention applied thereto;

45 Fig. 2 is a fragmentary cross sectional view taken on the line 2-3 of Fig. 1, showing the device set so that the ink rollers, indicated in dotted lines, will run over and ink the form, as indicated;

50 Fig. 3 is a similar view showing the de-

vice tripped, or in its raised position, so as to hold the rollers above the form, in the manner indicated, on their return trip;

Fig. 4 is a side elevation of the device apart from the form, with its side plate removed to show the interior construction, the bearing trip member being set, as in Fig. 2;

Fig. 5 is a similar view showing the bearing member tripped or raised, as in Fig. 3; and

Fig. 6 is a cross sectional view taken on line 6-6 of Fig. 5, with the side plate attached.

Referring now to the drawings, Fig. 1, A 65 designates a frame or chase, with a form B, clamped therein, in the usual manner, and with our invention also secured in place therein, and designated C-C, at the opposite ends or sides thereof.

The embodiment of the invention here shown for purposes of illustration comprises a long body composed of two plate members 1 and 2, with a slide plate 3, slidably mounted therebetween, and a trip bearing member 4 mounted thereupon and adapted to be raised and lowered in a manner now to be described. The plate 1 is recessed in its inner face to receive the slide plate 3, as indicated, which is provided with two inclined slideways 3^a-3^a, adapted to slidably receive the two guide members 4^a-4^a upon the trip bearing member 4. Said bearing member 4 is also provided with two straight pins, as 4^b-4^b, slidably seated between the body plates 1 and 2, and provided with coiled springs, as 4^c-4^c, normally operating to move the bearing member 4 to raised position. Said trip bearing member 4 is also provided with a spring-actuated plunger 5, 80 which fits over the slide plate 3 at its lower end and is provided thereat with a short pin or screw, as 6, adapted to move vertically in the notch 3^b in the slide plate 3, the upper end of which notch is formed into a round 85 seat 3^c into which said pin 6 fits when in its uppermost position. When in the raised or tripped position said bearing member 4 cannot be moved downwardly without first pressing said spring-actuated plunger 5 90

95

100

downwardly so as to move the screw 6 out of its seat 3^c in said slide plate 3. This permits said slide plate 3 to be moved lengthwise by the inclined guide members 4^a—4^a, 5 as said bearing member 4 is pressed downwardly. To this end the upper end of the plunger 5 projects slightly through the top of the bearing member 4, as indicated, so as to be first engaged by any surface pressing 10 upon said bearing members 4—4.

As a means for locking said slide plate 3 in its forward position and so as to hold said bearing member 4 in its set or down position, we have provided a lever 7, pivotally mounted and projecting from the end of the body, as indicated, with a hooked portion 7^a at its opposite end adapted to hook into a corresponding recess 3^a in the end of the slide plate 3. The projecting end of said lever is so positioned that it will be engaged by the rollers passing over the bearing member 4 in its set position. A spring-actuated plunger 8 is also mounted in the end of the body for normally raising the 25 outer or long end of said lever 7 so that it will automatically hook into the slide plate 3 when said slide plate 3 is moved to it by the pressing of the bearing plate 4 and the plunger 5 inwardly into the set position.

It will be noted that the slide plate 3, by reason of the inclined slideways 3^a—3^a, engages the guide members 4^a—4^a, in a way to prevent the bearing member 4 from rising under the tension of the springs 4^c, until the 35 slide plate is released and allowed to move longitudinally as the bearing member 4 moves outwardly. It will also be noted that the bearing member is locked against being pressed inwardly by the locking of the slide 40 plate 3 with the plunger 5 and pin or screw 6, making it necessary to first press said plunger 5 before the member 4 can be moved inwardly.

The operation of the invention can be 45 briefly described as follows: The devices are placed in the chase or frame at opposite sides thereof along with the form, as indicated by C—C, Fig. 1, with the trip levers 7—7 at the lower side thereof. The form is then 50 placed in the printing press in the usual manner, which need not be here illustrated, as it forms no part of the invention. Assuming that the bearing members 4—4 are down, or in their set positions, as shown in Fig. 2, the ink rollers pass downwardly over the form, applying the ink thereto in the usual manner. As they reach the bottom of the form, said rollers engage the trip levers 7—7 and release the bearing members 4—4, 55 which are at once moved into the tripped or raised position by the springs 4^c—4^c on the pins 4^b—4^b, and as shown in Fig. 3. As the rollers return to the inking plate of the press they run on the bearing members 4—4

out of engagement with the form B and thus 65 do not regather any of the ink from said form. This makes possible a very much better job than when the rollers gather up the ink in spots on their return trip. As the press closes and the impression is made from 70 the form B, said bearing members 4—4, with their plungers 5—5, are pressed inwardly at the same time and are thus again set so that as the rollers pass downwardly on their next trip, they engage and ink the form B, 75 as before, tripping the levers 7—7 as they reach the end of their travel downwardly, which causes the bearing members to be raised to carry the rollers free of the form on their up trip, as before explained. 80

We are aware that changes can be made in the embodiment of the invention as here illustrated and described without departing from the spirit of the invention, and we do not, therefore, limit the invention to the 25 particular embodiment here shown for illustrative purposes only, except as we may be limited by the hereto appended claims.

We claim,—

1. A roller trip for printing presses comprising one or more independent, detached devices adapted to be set bodily into a portable printing form, and each provided with a movable bearing member, means for holding said bearing member in an inoperative 95 position, and means adapted to be released by rollers passing thereover for automatically moving said bearing member into an operative position.

2. A roller trip for printing presses comprising a pair of self-contained members adapted to be inserted in a printing form at opposite sides thereof and each having movable bearing members, means for holding said bearing members in an inoperative position, means tending to move said bearing members into operative positions, and tripping means for releasing said bearing members, whereby they can be moved into operative positions, said tripping means being adapted to be operated by said rollers.

3. In combination with a detachable frame for holding a printing form, a roller trip adapted to be inserted in said frame, together with said printing form, said trip comprising two bearing members movably supported, means for holding said bearing members in inoperative positions within said frame, means normally tending to move said bearing members into operating positions, a tripping mechanism controlling the means for holding said bearing members in inoperative positions, said tripping mechanism projecting into the path of said rollers, whereby to be engaged and tripped thereby.

4. In combination with a printing frame and a printing form clamped therein, a pair of roller trips mounted within said frame

at opposite sides of the printing form and each comprising a body, a movable bearing member, means normally moving said bearing members beyond the plane of the printing form, means for holding said bearing members compressed below the plane of said printing form, said means operating automatically on said bearing members when they are compressed, and a tripping mechanism for releasing said bearing members, whereby they are automatically moved outwardly into operative positions, said tripping mechanism projecting into the path of said roller and operable thereby, substantially as described.

5. A roller trip for printing presses comprising a body, a bearing member movably mounted therein, means for locking said bearing member in its set or inoperative position, means tending to move said bearing member into its operative position, means for locking it in its operative position, means for tripping or releasing said bearing member from its inoperative position, and means for releasing it from its operative position.

6. A roller trip for printing presses comprising a body, a bearing member movably mounted therein, means operating to move said member into its operative position, a slide member for locking said bearing member in its operating or inoperating positions, and means for releasing said slide member.

7. A roller trip of the character referred to comprising a body, a bearing member movably mounted therein and movable to and from said body, a slide plate slidably mounted in said body and having operative connections with said bearing member, means operating to move said bearing member into its operating position, a trip member for holding said slide plate and said bearing member in inoperating positions, and a trip member for holding said slide plate and said bearing member in their tripped or operating positions.

8. In a roller trip of the character described, a bearing member adapted to be moved into operative and inoperative positions, a slide member having operating connections with said bearing member and adapted to move at an angle therewith, said slide member being adapted to lock said bearing member in either of its positions, means operating to automatically move said members in one direction, and a trip member for holding them against said movement.

9. In a roller trip of the character referred to, a body, a bearing member movably mounted therein and movable to and from said body, a slide member movable longitudinally of said body and having operating connections with said bearing member, means operating to automatically move said bearing member from said body, means for

locking said bearing member and slide member against movement from either of their positions, and means for releasing them, substantially as described.

10. A roller trip of the character referred to comprising a body adapted to be clamped in a printing form, a bearing member mounted thereupon with portions projecting into said body and being movable toward and from said body, a slide plate within said body, movable longitudinally thereof and having interlocking connections with said bearing member, springs for normally moving said bearing member from said body, a trip member for locking said slide member in one position with said bearing member in inoperative position, and a trip member for locking said slide member in its other position with said bearing member in its operating position, substantially as described.

11. A roller trip of the character referred to comprising a body adapted to be secured in a printing form, a bearing member mounted thereupon with portions projecting into said body and being movable to and from said body, means operating to move said bearing member away from said body, a slide member within said body and having interfitting connections with the projecting portions of said bearing member, said slide member being slidable longitudinally of said body and at right angles to the movement of said bearing member, a trip lever projecting from said body and adapted to lock said slide member in one position, and a trip member projecting above said bearing member and adapted to lock said slide member in its other position, substantially as described.

12. In combination with a printing press and the ink rollers thereof, of roller trip devices having bearing members adapted to be moved into and out of positions for supporting the ink rollers, with trip levers operable by said rollers to release said bearing members, and trip devices operable by said press for releasing and moving said bearing members into inoperative positions, substantially as described.

13. In a roller trip device of the character described, the combination with movable bearing members and means for moving the same, of a locking device projecting slightly beyond said bearing member and adapted to be operated to release said bearing member by pressure thereupon, substantially as described.

14. In combination with a printing press and the ink rollers thereof, of roller trip devices at opposite sides of the form and having bearing members movable into and out of positions for supporting the ink rollers from said form, means operating to move said bearing members into operating positions, a trip device on each for locking said

bearing members in inoperative position, said trip devices being operable by said ink rollers, and a trip device on each for locking said bearing members in their operative positions, said latter trip devices projecting slightly beyond said bearing members and adapted to be released by pressure thereupon, substantially as described.

Signed at Portland, Multnomah county, Oregon, this 3rd day of September, 1914. 10
